US0D1081379S

(12) **United States Design Patent** (10) Patent No.: **US D1,081,379 S**
(45) Date of Patent: ** Jul. 1, 2025

(54) **BOTTLE**

(71) Applicant: **STONEFALL, LLC**, Los Angeles, CA
(US)

(72) Inventors: **Eduard Kankanyan**, Yerevan (AM);
Levon Chkolyan, Yerevan (AM); **Anna Andranikyan**, Yerevan (AM); **Vaedan Harutyunyan**, Yerevan (AM)

(73) Assignee: **STONEFALL, LLC**, Los Angeles, CA
(US)

(**) Term: **15 Years**

(21) Appl. No.: **29/846,648**

(22) Filed: **Jul. 18, 2022**

(51) LOC (15) Cl. 09-01

(52) U.S. Cl.

USPC **D9/569**

(58) **Field of Classification Search**

USPC D9/569, 570, 559, 556, 549, 516, 520,
D9/538

CPC B65D 1/00; B65D 1/02; B65D 1/0223;
B65D 50/041; B65D 1/165

(57) **CLAIM**

The ornamental design for a bottle, as shown and described.

DESCRIPTION

FIG. 1 is a top perspective view of the bottle, showing our new design according to a first embodiment;

FIG. 2 is a bottom perspective view thereof;

FIG. 3 is a side view thereof;

FIG. 4 is a top view thereof;

FIG. 5 is a bottom view thereof;

FIG. 6 is a top perspective view of the bottle, according to a second embodiment;

FIG. 7 is a bottom perspective view thereof;

FIG. 8 is a side view thereof;

FIG. 9 is a top view thereof; and,

FIG. 10 is a bottom view thereof.

The broken lines shown in the drawings illustrate portions of the bottle that form no part of the claimed design.

The bottle is shown with a symbolic break within its height using a wavy broken line, and the portion of the bottle between the break lines forms no part of the claimed design.

1 Claim, 8 Drawing Sheets
